UNITED STATES PATENT OFFICE.

GEORGE S. HILL, OF STRAFFORD, NEW HAMPSHIRE, ASSIGNOR, BY MESNE ASSIGNMENTS, TO UNITED SHOE MACHINERY CORPORATION, OF PATERSON, NEW JERSEY, A CORPORATION OF NEW JERSEY.

SEWING-MACHINE.

1,352,514.

Specification of Letters Patent. Patented Sept. 14, 1920.

Application filed August 28, 1916. Serial No. 117,242.

To all whom it may concern:

Be it known that I, GEORGE S. HILL, a citizen of the United States, residing at Strafford, in the county of Strafford and State of New Hampshire, have invented certain new and useful Improvements in Sewing-Machines; and I do hereby declare the following to be a full, clear, and exact description of the invention, such as will enable others skilled in the art to which it appertains to make and use the same.

My invention relates to thread holding and severing mechanism for sewing machines.

15 The object of the invention is to provide novel and improved thread severing and holding means which will operate in a uniformly reliable manner to sever the standing needle thread close to the work, and 20 which is well adapted for use in buttonhole sewing machines in which a work clamp and the sewing mechanism are relatively actuated to form overseam stitches along the sides and about the end or ends of the buttonhole.

25 To these ends the invention consists in the features of construction and combinations of parts hereinafter described and referred to in the claims, the advantages of which will 30 be apparent to those skilled in the art from the following detailed description of the mechanism illustrated in the drawings, which embodies the invention in its preferred form.

35 In the drawings, Figure 1 is a sectional elevation showing so much of a buttonhole sewing machine as is necessary to illustrate the application of the present invention thereto. Fig. 2 is a side elevation partly in 40 section of the thread severing and holding mechanism, the parts being shown in the same position which is illustrated in Fig. 1. Fig. 3 is a plan view of the parts shown in Fig. 2. Figs. 4 and 5 are detail plan views 45 showing the thread severing and holding members in different positions, and Figs. 6, 7 and 8 are detail views showing the mode of operation of the mechanism.

In the drawings the invention is shown 50 as embodied in a buttonhole sewing machine having the construction and mode of operation of the machine shown and described in Patent No. 1,063,880, dated June 3, 1913. In this machine the stitch forming mecha-

nism comprises an upper needle 2 eccentrically mounted in a vertically reciprocating needle bar 4, and under needle 6, and a looper 8. The upper needle bar is mounted in a rotary head or carrier 10. The under needle and looper are mounted in a rotary 55 turret 12 which is rotated in unison with the head 10. The work is held by clamps 14 pivotally mounted on the work supporting plates 16, which are in turn mounted on a clamp carrier 18. The clamp carrier is 60 moved lengthwise of the buttonhole to bring the work into register with the cutter or with the sewing mechanism and to feed the work during the sewing by a cam groove 65 formed in the cam gear 20 which makes one revolution for each cycle of the machine. The clamp carrier is moved laterally and the stitch forming mechanism is rotated during the sewing through suitable connections 70 from a gear 22 which makes one revolution 75 during the sewing of a buttonhole. The cutter 24 is operated from a cam on the cam gear, and when operated to cut a buttonhole, also acts to close the clamps. The clamps are held closed during the sewing by latching devices, and are released during the return of the cutter carriage to cutting position, as fully described in the patent above referred to. At the completion of the sewing of a buttonhole the stitch forming mechanism is stopped with the upper and under 80 needles in their retracted positions, and with the upper needle thread about the looper, as 85 indicated in Fig. 1.

At the completion of the sewing the needle thread is severed close to the work and without materially deflecting it by thread severing and holding members which are normally in retracted position away from the needle path and which are advanced to 90 bring them close to and on opposite sides of the needle path and then retracted to sever and grip the thread and carry the severed end away from the needle path. In the construction shown the coöperating thread 95 gripping and severing members are mounted to move in unison in a supporting guide-way toward and away from the needle path and to move relatively to embrace and to sever and hold the thread and subsequently 100 to release the held end. The coöperating thread gripping and severing members are 105 formed or carried at the forward ends of

of two bars 26 and 28 which are mounted to slide in a guide way in the support 30. The support is carried on the lower end of a slide 32 which is guided in a bracket 34 secured to the head of the machine. The slide is forced downward by a spring 36 which tends to hold the head of a screw carried by the slide in engagement with the lower end of a slot in the bracket 34. The forward and return movements of the bar 26 are effected and controlled by cams 40 and 42 secured to the gear 20 and arranged to engage one arm of a lever 44 the other arm of which is connected by a link 46 with a cylindrical block 48 on the rear end of the bar. A spring 50 interposed between the rear end of the support 30 and the forward end of the link 46 tends to retain the bar 26 in its retracted position which is determined by the engagement of a stop screw 52 on the lever 44 with a fixed stop 54. The bar 28 is caused to advance with the bar 26 when permitted to do so by a spring 56 interposed between the rear end of the bar and the block 48. The bar 28 is caused to move back with the bar 26 by a lug 58 on the bar 26 which plays in a slot 60 in the side of the bar 28. The slot permits the bar 26 to advance independently of the bar 28 when forward movement of the bar 28 is arrested for the purpose of separating the thread gripping and severing members to embrace the standing thread or to release the held end as will be hereinafter explained. The movement of the bar 28 with the bar 26 is interrupted at certain times by a spring pressed latching pin 62 arranged to ride on the top of bar 28 and to enter notches 64 in the bar.

40 One of the thread holding and severing members consists of a thread engaging finger 66 projecting laterally from the forward end of the bar 26 into line with the bar 28. The finger is arranged to pass over the end of the bar 28 the upper edge of which forms a cutting member co-operating with the lower edge of the finger in severing the thread. The finger is also arranged to pass under the end of a flat spring plate 68 which is secured to the bar 28 and which forms a thread holding member co-operating with the upper surface of the finger in holding the end of the needle thread. The spring plate 68 has a lateral projection 70 overlying the bar 26 and acting to press the thin end portion of the bar down onto the end of the bar 28 which also has a laterally projecting portion 72 at its forward end and underlying the end of the bar 26. The end of the bar 26 just back of the finger 66 is somewhat thicker than the finger 66 and forms a cam for raising the end of the spring plate 68 when the finger is moved forward from under the plate to open the thread holding members and for

allowing the spring plate to close upon the thread as it is carried under the plate by the retraction of the finger.

During the sewing of the major part of the buttonhole the thread severing and holding members are held in closed and retracted position corresponding to the position indicated in Fig. 7. When in this position they are back away from the needle path and above the work clamp where they will not interfere with the proper operation of the sewing mechanism and clamp. As the sewing of the buttonhole is completed or is about to be completed the bar 26 is advanced by the cam 40. During the first part of this movement the bar 28 will move with the bar 26 until the pin 62 enters the forward notch 64 when the forward movement of the bar 28 will be interrupted. When the lug 58 on the bar 26 engages the forward end of the slot 60 in the bar 28, the bar 28 will be moved forward disengaging the notch from the pin so that the spring 56 will immediately advance the bar 28 with relation to the bar 26 until the rear end of the slot engages the lug 58. Thereafter the two bars will move forward together until a stop pin 74 on the bar 28 engages the rear end of support 30 and interrupts the forward movement of the bar 28. This occurs when the forward end of the bar 28 and the end of the spring plate 68 are close to the path of the needle in making its final stroke. The bar 28 is latched in this position by engagement of the pin 62 with the rear notch 64. After the movement of the bar 28 is arrested, the continued movement of the bar 26 advances the thread finger 66 across the needle path, thus opening the thread holding members and bringing them on opposite sides of the needle path or standing thread as indicated in Figs. 1, 2 and 3. After the sewing mechanism has stopped, the lever 44 rides off of the cam 40 and the bar 26 is retracted by the action of the spring 50. During the first part of the movement of the bar 26, the thread engagement finger 66 engages the standing thread close to the upper surface of the work and carries it under the end of the spring plate 68, the lower ends of the finger co-operating with the end of the bar 28 to sever the thread. As the thread engaging finger moves under the spring plate, the projection 70 on the plate 120 rides off of the cam back of the finger 66 so that the plate springs down and clamps the thread against the upper surface of the finger. During the continued backward movement of the bar 26 the lug 58 engages the end of the slot 60 and the bar 28 is retracted with the bar 26, the end of the severed needle thread being retained by the thread holding members and being carried back away from the needle path into the 130

position indicated in Fig. 7. When in this position the thread holding members hold the end of the thread leading to the needle in such position that the waste end of the 5 thread at the beginning of the succeeding buttonhole will be covered by the overseam stitches. While the initial stitches at the beginning of the succeeding buttonhole are being sewn the cam 42 acts to partially advance the bar 26. During this movement the latchpin 62 enters the forward notch in the bar 28 and arrests the forward movement of this bar so that the bar 26 moves forward independently of the bar 28 to 15 open the thread holding members and release the end of the thread. The parts then return to their normal position where they remain until the completion of the buttonhole when they are again operated to sever 20 and grip the standing thread and carry the severed end of the needle thread back and away from the needle path.

By the above construction the thread may be severed comparatively close to the work 25 without materially deflecting it between the last needle hole and the eye of the needle, and the thread holding devices may then be retracted to a position where they will not interfere with the subsequent operation of 30 the sewing and work feeding mechanism, and where if desired they may present the waste end of the thread in the position to be covered by the stitches at the beginning of the next buttonhole. It is preferred to 35 so arrange the supporting guide plate for the thread holding and severing members that these members will move in an inclined direction toward and away from the needle path, since by this arrangement the thread 40 may be severed closer to the work when arranged to move back and forth over the work clamp.

While it is preferred to employ the specific construction and arrangement of parts 45 shown and described in embodying the invention in the machine of the patent above referred to, it will be understood that this construction and arrangement is not essential to the broader features of the invention, 50 and may be varied and modified as found desirable or best suited to the machine in which it is to be incorporated.

Having explained the nature and object of the invention, and specifically described the 55 form of mechanism in which it may be embodied, what is claimed is:—

1. A sewing machine having in combination stitch forming mechanism including a reciprocating needle, a support provided 60 with a guideway, thread holding members movable in the guideway toward and away from the needle path, mechanism for simultaneously advancing the members to bring them close to the needle path, and for continuing the advance of one member inde-

pendently of the other to bring them on opposite sides of the needle path, and for retracting the members to grip the thread and then carry it away from the needle path, and means for severing the thread while the 70 holding members are close to the needle path and prior to their final retraction to holding position.

2. A sewing machine having in combination stitch forming mechanism including 75 a reciprocating needle, a support provided with a guideway, bars mounted to slide in the guideway, coöperating thread holding members at the forward ends of the bars, mechanism for simultaneously advancing 80 the bars to bring the members close to the needle path, for continuing the advance of one of the bars independently of the other to carry its thread holding member beyond the needle path and for retracting the bars, 85 to grip and sever the thread and then carry it away from the needle path.

3. A sewing machine having in combination stitch forming mechanism comprising a reciprocating needle and devices coöperating therewith to form overseam stitches, a work clamp, mechanism for relatively actuating the clamp and stitch forming mechanism to sew about a buttonhole, two bars mounted to reciprocate over the clamp toward and 90 away from the needle path, thread holding and severing devices carried at the forward ends of the bars, and mechanism for reciprocating the bars and giving one a limited 95 independent advance and return movement. 100

4. A sewing machine having in combination stitch forming mechanism including a reciprocating needle, a reciprocating bar having a laterally projecting thread engaging finger at its forward end, coöperating 105 thread holding and severing members mounted to reciprocate with the bar, and means for arresting the forward movement of the coöperating members before the bar completes its forward movement. 110

5. A sewing machine having in combination stitch forming mechanism including a reciprocating needle, sliding bars mounted for movement toward and from the needle path, thread severing and holding members 115 carried at the forward ends of the bars, connections between the bars permitting limited independent movement of one of the bars in each direction, and mechanism for reciprocating the latter bar. 120

6. A sewing machine having in combination stitch forming mechanism including a reciprocating needle, two sliding bars mounted for movement toward and from the needle path, thread severing and holding members carried at the forward ends of the bars, connections between the bars permitting limited independent advance and return movement of one of the bars to open 125 and close the thread holding and cutting 130

members when in advanced position, mechanism for reciprocating the latter bar and means for arresting the forward movement of the other bar before the advance of the reciprocated bar is completed.

7. A sewing machine having in combination stitch forming mechanism including a reciprocating needle, two sliding bars mounted for movement toward and from the needle path, thread severing and holding members at the forward ends of the bars, connections between the bars for causing them to move together and permitting limited independent advance and return movement of one of the bars, mechanism for reciprocating the latter bar, and a spring latch for interrupting the movement of the other bar.

8. A sewing machine having in combination stitch forming mechanism including a reciprocating needle, a reciprocating bar having a laterally projecting thread engaging finger at its forward end, a second bar mounted to reciprocate with the first, thread holding and cutting members at the forward end of the second bar, a yielding connection between the bars for causing the second bar to advance with the first bar and means for

advancing and retracting the first bar and arresting the forward movement of the second bar before the first bar completes its forward movement.

9. A sewing machine having in combination stitch forming mechanism including a reciprocating needle, a bar mounted for movement toward and away from the needle path, and having a laterally projecting thread engaging finger at its forward end, a spring plate under which the finger carries the thread, and a cam surface on the bar for raising and lowering the plate.

10. A sewing machine, having, in combination, stitch forming mechanism including a reciprocating needle, sliding bars mounted for movement toward and from the needle path, thread severing and holding devices carried at the forward ends of the bars, and mechanism for advancing and retracting the bars together and for giving one a limited independent movement in one direction to open the holding devices and in the other direction to actuate the holding and severing devices to sever and grip the thread.

GEORGE S. HILL.
